N. B. DOUGLASS,
WALL OR CABINET BED,
APPLICATION FILED NOV. 18, 1908.

939,482.

Patented Nov. 9, 1909.

UNITED STATES PATENT OFFICE.

NAPOLEON B. DOUGLASS, OF SEATTLE, WASHINGTON.

WALL OR CABINET BED.

939,482.

Specification of Letters Patent.

Patented Nov. 9, 1909.

Application filed November 18, 1908. Serial No. 463,291.

To all whom it may concern:

Be it known that I, NAPOLEON B. DOUGLASS, a citizen of the United States of America, and a resident of the city of Seattle, in the county of King and State of Washington, have invented certain new and useful Improvements in Wall or Cabinet Beds, of which the following is a specification.

My invention aims to provide a bed of the above type which may be folded or opened with ease, and when opened will be in a relatively projected position so that the head thereof will be practically entirely outside of the closet or recess in which the same is arranged when closed.

Other objects will be set forth as the description progresses and those structural features, arrangements and combinations of parts in which my invention resides, succinctly defined in my annexed claims.

Referring now to the accompanying drawing, in which my invention in a form now preferred by me, is illustrated, Figure 1 is a side view partly in section showing my bed in closed position. Fig. 2 is a similar view showing the bed open, or in position for use, and Figs. 3 and 4 are detail fragmentary views, on enlarged scale, illustrating more particularly the swingingly supported leg.

Referring to the drawing by numerals of reference, 1 indicates the jamb of the cabinet which may be set into the wall of a room or otherwise provided. Within said jamb is supported by hangers 2, the bed frame to the outer side of which is secured the closure panel 3. Hangers 2 are secured at 3' to the sides of said jamb and as at 5 to the side rails 4 of the bed frame, thereby supporting said frame for vertical swinging to and from a closed position and also for swinging bodily outwardly of the said cabinet or recess. Side rails 4 are provided at their inner end portions with extensions or arms 6, having bearing members 7 which may be in the form of rollers, as shown, for engagement with tracks 8, which tracks are arranged to be engaged by said bearing members, during opening movement of the bed, so that in traveling through their arc-like paths said bearing members will by engaging said tracks force the bed frame outwardly to the position shown in Fig. 2, hangers 2 swinging on pivots 3' during this operation and consequently lifting to a slight degree the inner end portion of the bed

frame. Tracks 8 are preferably flexible and connected to the floor and to suitable take up devices, as 9 on the jamb, as shown. By providing tracks 8 of the cable or other suitable flexible material and of such length that 60 they will lie comparatively slack when the bed is in closed position, a construction is provided wherein projection and retraction of the bed is effected without jar or an abrupt action.

Reference numeral 10 indicates the head closure panel for the cabinet or recess in the wall of the room the same being hinged, as at 11 to a relatively fixed wall section 12 of the frame for movement therewith. Wall 70 section 12, as now considered provides a compartment or chamber 13 adapted for reception of counter balancing weights 14. Panel 10 is guided in its upward movement by forwardly extending arms 22, which are 75 pivoted at 22' to the side of jamb 1, which construction is compact and therefore very desirable, especially when the bed is arranged in the recess in a wall.

Legs, as 15 are provided preferably on 80 each side of the free end portions of the bed frame, the same being pivotally supported in slots 16 of panel 3 and adapted, when in closed position, to engage in recesses or seats 17, extending from said slots 16, as shown. 85 To effect the swinging of legs 15 to an open position simultaneously with the projection of the bed frame, I provide said legs with extensions 18, to which one end of flexible connections, as 19, are connected, the other 90 ends of said connections being secured at 20 to the jamb. Extensions 18, are provided with curved surface portions, as 18', on which flexible connections 19 engage when the legs are in closed position, to enable a 95 desired purchase being had to effect the opening movement of said legs. When the bed frame is swung upwardly, legs 15 swing by gravity to a closed position and springs, as 21 bearing thereon tend to hold the same 100 against accidental outward movement.

Having thus fully described my invention, what I claim as new and desire to secure by Letters Patent of the United States, is:

1. A cabinet or wall bed comprising a casing, a frame provided with a bearing member, means for suspending said frame in vertical position for swinging movement to its lowered position and for bodily move- 110

ment in an outward direction, and a flexible track secured to said casing at points above and below the lower end of said frame and arranged for engagement by the bearing member on said frame to effect bodily movement of said frame in an outward direction during swinging thereof to its lowered position.

2. A cabinet or wall bed comprising a frame provided with a bearing member, means for suspending said frame in vertical position for swinging movement to its lowered position and for bodily movement in an outward direction, and a flexible track arranged for engagement by the bearing member on said frame to effect bodily movement of said frame in an outward direction dur-

ing swinging thereof to its lowered position.

3. A cabinet or wall bed comprising a casing, a frame, hangers pivoted to said casing and to said frame, said frame being provided with a bearing member, and a flexible track carried by said casing and arranged to be engaged by said bearing member and have the latter travel thereon to effect bodily movement of said frame in an outward direction. 25

Signed at Seattle, Washington this 10th day of November 1908.

NAPOLEON B. DOUGLASS.
